UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

DOUBLE-DRUM HOIST.

Application filed September 11, 1925. Serial No. 55,679.

This invention relates to double drum hoists, more especially to a hoist of the general type shown in Reissue Patent No. 15,780 granted March 4, 1924 to Jesse Ditson, in which either drum may be driven from a common driving shaft connected to be operated by a reversible motor.

The objects of the invention are to lighten the construction of such hoists and at the same time brace and stiffen the frame and reduce the vibration.

The invention is shown in one of its preferred forms in the accompanying drawings, in which

15 Figure 1 is a longitudinal sectional elevation of a hoist;

Figure 2 is a transverse sectional view on the line 2—2 of Figure 1 looking in the direction of the arrows;

20 Figure 3 is a detail view partly broken away, similar to Figure 2, showing the pawl in a different position.

Referring to the drawings, the main frame consists of a base A and end frames

25 B and C. The supplemental end frame D in this instance forms the back head of a pressure fluid motor and constitutes a part of the end frame B. The front head E of the motor is bolted to the frames B and D

30 as by means of the bolts F. The motor itself may be of any suitable type but in this instance is a flat piston or Dake motor, like that disclosed in said Ditson Reissue Patent No. 15,780, and is of the reversible type, the pressure fluid being controlled by the throttle handle G. Only so much of the motor

35 parts are shown as will indicate the type of motor, and as illustrated the upper portion of the end frame B forms a square piston chamber H in which the outer frame piston J reciprocates, and an inner piston K reciprocates at right angles to the frame piston J. The resultant of forces imparts rotation to the crank L of the main shaft O

40 which is journaled in the end frames and provided with the anti-friction bearings P. A hollow rotatable center bearing Q is also journaled in the end frames forming a drum shaft and is provided with the anti-friction

45 bearings P'. The main shaft O is preferably within the hollow center bearing Q. Drums S and T are rotatably mounted relatively to the hollow center bearing Q, and in this instance

the drum T rotates upon the extension U 55 of the drum S. The drums may be conveniently provided with the bearing sleeves V and W, respectively.

A main driver X, shown in this instance as an internal gear, is connected to one end 60 of the center bearing as by means of the key Y and is geared to the main shaft O by suitable reduction gearing. In this instance, a pinion a on the end of the main shaft O meshes with an intermediate gear b 65 on the countershaft c having the anti-friction bearings d and provided with the pinion e meshing with the internal gear or main driver X. The end frame C also constitutes the gear box having the cover plate f 70 and caps g and h.

The drums S and T have wound upon them the usual haulage and tail ropes j and k, and in the present construction S may be considered the haulage drum and T the tail rope drum, these functions being reversed according to the direction of rotation of the motor.

The drums are provided with drum drivers, in this instance shown as toothed rings 80 o and p having teeth q and r facing in opposite directions. A pawl or clutch member s is slidably carried between the projecting lugs t on the main driver X in position between the drum drivers so that said pawl 85 may automatically be shifted into engagement with one drum driver or the other, according to the direction of the rotation of the motor, as in said Reissue Patent No. 15,780.

In Figure 2 the main shaft O is assumed to be rotating clockwise, as the figure is viewed, while the rotatable center bearing or drum shaft Q is being rotated counter-clockwise through the train of gearing described and the main driver X. The pawl s has been actuated by the backs u of the teeth r on the drum driver p of the haulage drum S into engagement with a tooth q of the drum driver o of the tail rope drum T, 100 so that the tail rope drum winds up the rope k and hauls the load. The reverse of this operation is indicated in Figure 3, in which the pawl s is shown in engagement with one of the teeth r of the drum driver p of the haulage drum S, which is then connected to haul the load.

In a hoist of this type there is consid-

erable strain upon the frame due to the loads carried and due to the vibration set up by the motor, and although the center bearing *Q* is of substantial construction and braces the frame and takes a considerable portion of the load, there is a tendency for the end frames to separate and vibrate. In order to counteract this tendency, reduce vibration and stiffen the frame, a cross brace, 10 preferably in the form of a bar or rod *Z*, is connected between the outer free ends of the main portions of the end frames.

This bracing device may be constructed in any suitable manner and is not necessarily a rod or bar, although so shown in the present instance. This bar *Z* is preferably provided with the washers *v* and the spacing sleeve *w* between the said bearing washers. The bar *Z* is preferably constructed in the form of a bolt having the head *x* and the nut *y* for pinning the bolt in place. This cross brace also acts as a guide and deflector for the ropes or cables *j* and *k*, tending to confine the cables between the drum flanges and prevent the cables from becoming tangled. 20

One or both drums may be provided with brake bands 2 extending partially over the drum flanges and secured at their lower ends 30 to the brackets 3 on the base *A*. The upper ends of the brake bands are conveniently supported by the brace bar *Z* as by means of the sleeves 4 pivoted on the bar *Z* and having rings 5 through which the screw 35 threaded ends 6 on the brake bands extend. Wing nuts 7 serve as adjusting devices for the brakes.

I claim:

1. In a double drum hoist, the combination of a base and end frames, a reversible 40 motor, a hollow rotatable center bearing journaled in said end frames and forming a drum shaft, concentric drums rotatably mounted relatively to the hollow center bearing, a main shaft within the center 45 bearing also journaled in the end frames, a main driver connected to said center bearing and geared to the main shaft, a clutch member on the main driver adapted to connect either drum to the said main driver, a cross brace connecting the outer free ends of the end frames to stiffen the frame structure, and drum brakes anchored pivotally to the cross brace for checking rotation of the drums. 50

2. In a double drum hoist, the combination of a base and end frames, a reversible motor, a hollow rotatable center bearing journaled in said end frames and forming a drum shaft, drums rotatably mounted relatively to the hollow center bearing, a main shaft within the center bearing, a main driver connected to one end of said center bearing and geared to the main shaft, a clutch member on the main driver adapted to connect either drum to the said main driver, a cross brace connecting the outer free ends of the end frames to stiffen the frame structure, and a drum brake supported at one end by said cross brace and anchored at its other end to the base. 55

In testimony whereof I have signed this specification.

CHARLES C. HANSEN.
